CLAIM

The ornamental design for an ear clip, as shown and described.

DESCRIPTION

FIG. 1 is a rear perspective view of an ear clip;
FIG. 2 is a rear elevation view of the ear clip;
FIG. 3 is a front elevation view of the ear clip;
FIG. 4 is left side elevation view of the ear clip
FIG. 5 is right side elevation view of the ear clip;
FIG. 6 is a top view of the ear clip; and,
FIG. 7 is a bottom view of the ear clip.

The broken lines represent portions of the ear clip that form no part of the claimed design. The dash-dot-dash line represents the boundary of the claimed region. The strap is shown with symbolic breaks in its length; the appearance of any portion of the article between the break lines forms no part of the claimed design.
